FRONT WALL OF A MOBILE HOME

John R. Lonergan, Elkhart, Ind., assignor to Lonergan Corporation, Elkhart, Ind., a corporation of Indiana

Filed Feb. 21, 1964, Ser. No. 78,768

Term of patent 14 years

(Cl. D14—3)

FIG. 1

The broken-line representations in FIGURES 1 and 3 of the body of a mobile home are for the purposes of illustration only.

I claim:

The ornamental design for a front wall of a mobile home, substantially as shown and described.
